THOMAS I. POTTER, OF PORTLAND, OREGON.

REFRIGERATING UNIT.

Application filed November 10, 1926. Serial No. 147,534.

This invention relates generally to the art of mechanical refrigeration and applies equally well to large and small installations.

The main object of this invention is to provide an exceedingly simple and efficient refrigerating machine employing the compression principle and using a volatile liquid as a refrigerant.

The second object is to construct a special type of compressor unit in which an oscillating cylinder is employed, which cylinder is held to its seat by the combined action of a spring and pressure within the compressor case.

The third object is to provide an elevated reservoir to form a lubricant seal over the usual packing to insure a gas tight fit at the point where the power shaft enters the compressor case without the necessity of having an undesirably high oil level in the compressor case.

The fourth object is to employ the accumulator or receiver as a separator for the refrigerant and the lubricant and connect the lubricant in the accumulator with the lubricant in the compressor, thereby preventing any excess accumulation of lubricant in the accumulator, or lack of lubricant in the compressor.

The fifth object is to utilize the well known tendency of refrigerants and lubricants of different specific gravities to separate as a means for returning to the compressor case any lubricant which may have been carried over with the refrigerant passing through the compressor.

The sixth object is to provide an improved form of expansion chamber in which the usual coils are dispensed with, thereby effecting a considerable saving in space, which is an important item in small units.

The seventh object is to so arrange the ports of the compressor as to avoid possible knocks due to trapped liquids, or loss of efficiency due to trapped gases being compressed instead of expelled.

These objects are accomplished in the manner set forth in the following specification as illustrated in the accompanying drawings, in which:

Fig. 1 is a somewhat diagrammatic section taken through the assembled elements of the machine. Fig. 2 is a horizontal section taken along the line 2—2 in Fig. 1. Fig. 3 is a vertical section taken along the line 3—3 in Fig. 1. Fig. 4 is a transverse

section through the compressor taken along the line 4—4 in Fig. 1. Fig. 5 is a horizontal section through the cylinder of the compressor taken along the line 5—5 in Fig. 4. Fig. 6 is a horizontal section through the manifold taken along the line 6—6 in Fig. 4 and showing the relation of the manifold passages and cylinder ports during one position of the cycle, and Fig. 7 is a similar view showing the relation of the same parts in the extreme opposite position of the cycle. Fig. 8 is a perspective view of one of the cylinders. Fig. 9 is a fragmentary section showing the relation of the cylinder ports and compressor ports when the eccentrics are on the dead center for a cylinder at full compression.

Similar numbers of reference refer to similar parts throughout the several views.

Referring in detail to the drawings, there is illustrated a refrigerator 10 including a special type of expansion chamber 11 whose lower outlet pipe 12 connects with the intake side of the compressor 13 from which the compressor discharge pipe 14 extends to the condensing coil 15 which, in this instance, is air-cooled by the fan 16 on the shaft of the motor 17.

The belt 18 from the motor 17 drives the compressor shaft 19, which passes through the gland 20 of the compressor 13, and journals in the bearings 21 and 22 within the compressor case. Above the bearings 21 and 22 are formed the oil pockets 21^A and 22^A to insure proper lubrication of the bearings, and in the case of bearing 22 to provide an oil seal against the packing 24 to prevent the escape of gaseous refrigerant through the packing. Since it is not difficult to hold a lubricant it can be seen that the usual loss of refrigerant is thus eliminated.

On the shaft 19 between the bearings 21 and 22 are secured the two eccentrics 25 and 26 which drive the pistons 27 and 28 of the cylinders 29 and 30. Each of the cylinders 29 and 30 has formed thereon a cylindrical trunnion 31 through which passes a port 32. Oil grooves 33 are also provided in the sides of the member 31 whose side portions 31^A 105 are cut away to reduce friction.

The member 31 can oscillate within the cylindrical head 34 of the compressor in which are formed the enlarged ports 35, 36, 37 and 38. An intake passage 39 which joins the ports 35 and 37 of the pipe 12, and a discharge passage 40 which joins the ports

36 and 38 to the pipe 14 are formed in the manifold 41, which is bolted on to the member 34. Between the receiver 45 and the compressor case 42 is a pressure balancing pipe 43.

It will be noted in Fig. 9 that the lap on the exhaust port is zero when the crank is on center. This prevents any gas or liquid which may be in the cylinder or its port opening from being trapped therein, which would cause a knock if a liquid were trapped and a loss of efficiency if gas was not completely discharged from the cylinder. Lap is, however, provided on the intake port side.

15 The condensing coil discharges into the top of the accumulator or receiver 45 which is provided with a sight glass 46 and an oil discharge pipe 47 which empties into the compressor case 42. A discharge pipe 48 for liquid refrigerant is connected with the receiver well above the pipe 47 and carries the liquid refrigerant 49 to the expansion valve 50. The lubricant 51 may be any of those suitable for use with the particular refrigerant being employed.

20 In the construction of the cylinders 29 and 30 it is preferable to so form the members 31 that they must be compressed in order to place them in position. The spring action thus secured tends to hold the cylinder to its seat, to which is added the outward thrust on the cylinder caused by the pressure within the compressor case itself.

25 The expansion chamber 11 includes a number of spaced floors 53 and 54 having a plurality of ribs 55 between same, preferably with angular spacing which will provide the maximum amount of travel for the refrigerant and for the purpose of securing 30 more uniform distribution of the refrigeration. The members 53 and 54 can be built up in sections and joined to a common front 56 by means of the bolts 57. The members 53 slope alternately from one side to the other for drainage purposes.

40 The operation of the device is as follows: Assuming that a suitable supply of lubricant and refrigerant have been placed in the accumulator 45 it will be seen that if a heavier lubricant is used it will settle to the bottom of the accumulator and some of it will flow through the pipe 47 into the compressor case.

45 The upper and lighter refrigerant will cause the level of lubricant 50 in the accumulator to be somewhat below the level of the lubricant 50 in the compressor. If the motor 17 is now operated it will cause the pistons 27 and 28 to draw a partial vacuum on the pipe 12, which draws warmed refrigerant from the expansion chamber and forces same through the coil 15 under pressure. Heat is taken from the coil 15 by the fan 16, causing the liquid refrigerant thus 55 formed, together with any oil which may

have passed over from the compressor, to fall into the accumulator in a somewhat mixed condition, but which, due to their different specific gravities, soon separate leaving the lubricant at the bottom.

70

There can be no undue accumulation of refrigerant or lubricant in the wrong compartment, since the oil will seek its own level, due to the fact that there is a constant state of balance of pressures in the compressor case and in the receiver due to the pipe 43. Should any refrigerant pass over with the lubricant through the pipe 47 the heat within the compressor will soon 75 gasify same, causing it to escape through the pipe 43 from which it re-enters the receiver 45.

80 It must be understood that while in this specification the lubricant is being referred to as the heavier of the two liquids employed, this of course is not necessarily the case. If the lubricant is lighter it is only necessary to reverse the relation of the pipes 47 and 48 and correct the elevation of the accumulator 45 by lowering same, as is well 85 understood.

85 In Figure 7 it will be observed that the side portions 58 of the members 31 are cut away to increase the thrust of the spring against the seated area around the port 32.

90 I am aware that many forms of refrigerating machines have been constructed in the past and that the broad idea of securing mechanical refrigeration on what is known as the compression principle has long been used; it is therefore not my intention to cover this method of refrigeration except as specified in the appended claims.

I claim:

1. In a refrigerating machine, the combination of a compressor having an oil well formed therein with a separating compartment in which mixed oil and refrigerant can separate by gravitation, together with a duct for carrying such separated oil back to 105 said well by gravity; and an open connection between the separator and well above their highest liquid levels.

2. In a refrigerating machine, the combination of a compressor having a well for 115 lubricant formed therein; a chamber in which refrigerant and lubricant of different specific gravity can separate by gravitation; a duct discharging from the lubricant containing portion of the chamber into said 120 well by gravity; and an open connection between the spaces above the liquids in said compressor and said chamber.

3. In a refrigerating machine, the combination of an expansion unit; a compressor intaking from said expansion unit; a condensing unit into which said compressor discharges; a connecting passage for lubricant 125 between the lubricant holding portion of the condenser and of the crank case of the com- 130

pressor adapted to permit lubricant from said condenser to gravitate to said crank case; and a second connection between the compressor case and the condenser above 5 their liquid levels.

4. The combination of a compressor having a case around its actuating mechanism suitable for withstanding several atmospheres of pressure; a condenser unit for low 10 specific gravity refrigerant and for higher specific gravity lubricant having its lower end connected to the compressor case; and having a pressure balancing pipe between the case of said compressor above its oil 15 line and connecting with the condensing unit at a point above its highest liquid level.

5. A refrigerating unit having, in combination, an accumulator; a condenser discharging into said accumulator; an expansion system; a compressor between said expansion system and said condenser; an expansion valve between said expansion system and said accumulator; means for balancing the pressures in the case of said 20 compressor and said accumulator; and an oil 25 passage from said accumulator to the case of said compressor.

6. In a refrigerating unit, the combination of an accumulating tank; a condensing coil 30 discharging into said tank; an expansion system; a compressor drawing heated refrigerant from said expansion system and forcing same through said condenser; an oil-carrying duct connecting the bottom of the 35 compressor case with the bottom of the accumulator discharging into the compressor

case; an expansion valve for admitting refrigerant from said accumulator to said expansion chamber; and a pressure balancing pipe between said compressor case and the 40 accumulator.

7. A refrigerating unit having, in combination, an accumulator and an expansion chamber with a condensing coil between one end of said expansion chamber and the top 45 of said accumulator; a compressor adapted to draw warm refrigerant from said expansion chamber and force same through said coil under increased pressure, said pressure being maintained within the accumulator and within the case of said compressor; said compressor and said accumulator having an oil pipe connecting their lower 50 ends; a pressure balancing pipe between the case of said compressor and the accumulator; and a mechanically operated valve 55 adapted to release quantities of liquid refrigerant from said accumulator into said expansion chamber in an intermittent and adjustable flow.

8. In a refrigerating machine, the combination of a compressor; a condensing unit for containing a refrigerant and a lubricant; an expansion unit; a connection from the oil level of the condensing unit to the oil 65 level of the crank case of the compressor unit adapted to permit lubricant from said condenser to gravitate to said crank case, with a further connection from the crank case to the condensing unit at a higher or 70 gas level.

THOMAS I. POTTER.
